[57] CLAIM

The ornamental design for a digital clock, as shown and described.

DESCRIPTION

FIG. 1 is a right front perspective view of a digital clock showing my new design;

FIG. 2 is a right front perspective view of another embodiment of my new design of FIG. 1;

FIG. 3 is a front elevational view of both FIGS. 1 and 2;

FIG. 4 is a rear elevational view of FIG. 1;

FIG. 5 is a top plan view of both FIGS. 1 and 2;

FIG. 6 is a right side elevational view of both FIGS. 1 and 2, and the left sides being mirror images thereto;

FIG. 7 is a bottom plan view of FIG. 1;

FIG. 8 is a bottom plan view of FIG. 2;

FIG. 9 is a rear elevational view of FIG. 2.
